UNITED STATES PATENT OFFICE.

GUSTAVE GIN, OF PARIS, FRANCE, ASSIGNOR TO FRANCIS B. CROCKER, OF NEW YORK, N. Y.

ELECTRIC FURNACE FOR TRANSFORMING PIG-IRON INTO STEEL.

970,700.

Specification of Letters Patent. Patented Sept. 20, 1910.

Application filed January 25, 1906. Serial No. 297,855.

To all whom it may concern:

Be it known that I, GUSTAVE GIN, a citizen of the French Republic, and a resident of Paris, 43 Rue de Levis, have invented 5 certain new and useful Improvements in Electric Furnaces for Transforming Pig-Iron into Steel, of which the following is a specification.

This invention relates to electric furnaces, 10 and particularly to furnaces of this class especially adapted for transforming pig-iron into steel, and constitutes an improvement upon the furnace for the manufacture of steel forming the subject matter of Letters 15 Patent Number 771,872, granted to me October 11th, 1904.

In the accompanying drawing in which like reference letters designate corresponding parts throughout the several views, Figure 1 is a plan view showing fused metal 20 as it appears in one form of channel which I provide in the hearth of my furnace. Figs. 2, 3 and 4 illustrate in plan view molten metal in channels of other shape. 25 Fig. 5 is a longitudinal sectional view of a preferred form of my furnace. Figs. 6 and 8 are cross sectional views taken on lines 6—6 and 8—8 respectively of Fig. 5, and, Fig. 7 is a horizontal sectional view of the 30 said furnace.

The electric furnace set forth in my Patent Number 771,872 hereinbefore referred to was provided with steel electrodes which might be objectionable if the furnace was 35 used for any other purpose than refining steel, and would be a serious obstacle in case the furnace was used to produce any other metal than iron in a pure state.

It is the general purpose of this invention 40 to avoid the use of electrodes, and to employ in lieu thereof means to generate in molten metal contained in one or more endless channels an induced current of electricity. In doing this I employ a hearth of suitable refractory material having in the upper surface thereof one or more crucibles of annular form in which the material to be operated upon forms a closed electrical circuit. In connection with the annular crucibles I 45 employ a magnet having portions thereof extending from without the furnace within the annular crucible or crucibles. The mag-

net is provided with a suitable primary winding outside of the furnace, and has portions extending above and below each of the 55 annular crucibles, and joined within said crucibles as illustrated in Figs. 1, 2, 3 and 4. The parts are so arranged that a current of electricity passing through the primary winding or coil will generate an induced 60 current in the metal in the annular crucibles, this current being transformed into heat in its passage through the metal in the crucibles.

In Fig. 1 I have illustrated metal A contained in one form of endless crucible. A single magnet B', provided with the primary winding or coil C' is employed to generate a current in the metal A, as heretofore described.

In the form of apparatus shown in Fig. 2 the metal A is treated in three elongated parallel endless channels, disposed as shown. In this form of my invention I employ a magnet B² having three arms b² extending 75 within the separate closed channels, as shown.

Fig. 3 shows a form of construction in which the metal A is contained in two parallel endless channels. The magnet B has 80 two arms and a single primary coil C, as shown.

Fig. 4 illustrates a form of my invention in which the metal A is contained within three parallel channels, joined at their ends, 85 as illustrated. In connection with this form of crucible I employ a magnet B⁴ having a double coil provided with similar windings C⁴, but wound in opposite directions. These windings may be connected in 90 series or parallel as preferred. In this construction, the intensity of the current induced in the central channel will be twice as great as that in the outer channels.

In Figs. 4, 5, 6 and 7 I have illustrated a 95 furnace embodying my invention in practical form.

I have selected for detailed illustration the form of my invention shown in Fig. 3, the construction of a furnace having crucibles of other shapes illustrated will be 100 obvious however from the illustration and description of the form selected.

The furnace contains a hearth of noncon-

ducting refractory material which may be inclosed in a suitable metallic frame. In the hearth are dug channels of the form illustrated in Fig. 3. These channels are 5 shown as containing metal A. The magnets B are made of laminated sheet iron, and are united by the core C', on which the primary coil C is wound. These windings being outside of the furnace, may be successfully protected from the heat of the molten metal. The vertical portions of the magnet in the vertical chambers D are within the annular channels, so that the magnets encircle the circuits formed by the metal in the channel. 10 The furnace is provided with a pivotal support at its lower part, as shown. The furnace is tilted or oscillated on this pivotal support by means of screw jack F, which may be driven by hand or by power. 15 The operation is ended, the refined metal is run off through the orifice G, while the orifices H remain closed. When the running off is terminated, the orifice G is closed with a plug; and the communicating orifices H 20 are opened. The metal of the first crucible then runs into the second one. The furnace is then brought back to its horizontal position and the first crucible is filled with a quantity of pig-iron and scrap iron, equivalent to that which has been taken out. 25 It will be observed by reference to the drawings, *e. g.*, Fig. 3, that my said crucibles or channels are of substantially the same cross sectional area throughout, and, as I 30 have stated, elongated, endless and parallel, and that said crucibles or channels comprise extended portions folded back into parallelism with each other; also that, as illustrated in Figs. 1, 2, 3 and 4, the energizing 35 magnet is so disposed relatively to said parallel portions that parts of latter lie relatively outside of the magnetic influence and so close to each other as to largely reduce self induction and reactance, the distance of 40 said parts from said magnet being much greater than the diameter of the horizontal cross-section of said magnet taken in the plane of said crucible. 45 Having described my invention, I claim: 50 1. In an induction furnace a hearth comprising a horizontally disposed endless crucible or channel of substantially the same cross-sectional area throughout, said channel inclosing elongated portions, adjacent one 55 end of said elongated portions an electro-magnet adapted to set up an induced electric current in metal contained in said crucible, parts of the said channel being so far

elongated from said magnet as to lie relatively outside of the magnetic influence and 65 parallel and so close to each other as to largely reduce self-induction and reactance. 60

2. In an induction furnace a hearth comprising a horizontally disposed endless crucible or channel of substantially the same 70 cross-sectional area throughout, and an electromagnet having a part thereof disposed within the space surrounded by said crucible, said crucible comprising portions thereof disposed parallel with each other, and so 75 close to each other as to largely reduce self-induction and reactance and at a distance from said magnet not less than the diameter of its horizontal cross-section taken in the plane of said crucible. 80

3. In an induction furnace a hearth comprising a horizontally disposed endless crucible or channel, of substantially the same cross-sectional area throughout, disposed to encompass two portions of said hearth, and 85 two electro-magnets each having a part thereof disposed within one of said portions of said hearth and each having a coil wound oppositely to the coil of its adjacent electromagnet, whereby the intensity of the current 90 in metal contained in that portion of said crucible extending between said portions of said hearth is greater than in metal contained in other portions of said crucible. 95

4. In an induction furnace a hearth comprising a plurality of horizontally disposed endless crucibles or channels of substantially the same cross-sectional area throughout and an electro-magnet having a like plurality of arms, one of which arms is disposed within 100 each one of the spaces surrounded by each said crucibles or channels, each of said crucibles comprising portions parallel with each other and so far elongated from its proximate arm of said magnet as to lie relatively 105 outside of the magnetic influence and so close to each other as to largely reduce self-induction and reaction. 110

5. In a furnace of the type set forth, a hearth provided with a plurality of endless 115 crucibles or channels inclosing a plurality of elongated portions of said hearth, and one or more electro-magnets disposed in juxtaposition to one end of said elongated portions, said electro-magnet or magnets being provided with one or more energizing coils disposed exteriorly of said crucibles or channels, and said electro-magnet or magnets having a plurality of arms extending within portions of said hearth inclosed by said crucibles or channels, substantially as described. 120

6. In a furnace of the type set forth, a hearth provided with a plurality of endless crucibles or channels inclosing a plurality of 125 elongated portions of said hearth, and one

or more electro-magnets having a plurality of juxtaposed cores disposed in juxtaposition to one end of said elongated portions, coils surrounding said cores, said coils being oppositely wound on adjacent cores, and said electro-magnet or magnets having a plurality of arms connected with said cores and

extending within the portions of said hearth surrounded by said crucibles or channels substantially as described.

GUSTAVE GIN.
